FIG-9

FIG-11

FIG. 1 is a front perspective view of an eye make-up kit showing my new design in closed position;

FIG. 2 is a rear bottom perspective view thereof;

FIG. 3 is a top plan view;

FIG. 4 is a bottom plan view;

FIG. 5 is a front elevational view;

FIG. 6 is a rear elevational view;

FIG. 7 is a left side elevational view;

FIG. 8 is a perspective view of the make-up kit in open position;

FIG. 9 is a left side elevational view thereof;

FIG. 10 is an elevational view of the inside lid thereof; and

FIG. 11 is a top plan view of the open kit.

I claim:

The ornamental design for an eye make-up kit, substantially as shown and described.
